UNITED STATES PATENT OFFICE.

GEORGE M. BECHTEL, OF MONTCLAIR, NEW JERSEY.

CONTENTS-LEVEL INDICATOR FOR CONTAINERS.

Application filed February 4, 1926. Serial No. 86,018.

The invention relates to improvements in devices for indicating the level of the contents of a container, such as a tank or bin, and my object is to provide an exceptionally efficient indicating device of this character which will operate to equal advantage, regardless of the nature of the contents. The device may find its most extensive use in connection with bins for holding coal in a more or less powdered state or in connection with seed and grain bins, but it will operate effectively whether the contents be dry, moist, or wet, and whether such contents be fluid, semi-fluid, gelatinous, viscous, granular, etc.

With the foregoing in view, the invention resides in the novel subject matter herein-after described and claimed, the description being supplemented by the accompanying drawings.

Figure 1 is a side elevation partly broken away, illustrating the invention.

Fig. 2 is a detail end elevation of certain parts shown in Fig. 1.

In the drawings above briefly described, the numeral 3 designates a container which may be of any desired type and may hold contents of any nature. Operatively associated with this container, is the improved level indicating means, and it may be stated that the gist of the present invention resides in unique automatic operating means for practically any sort of an indicator, the purpose of which is continuously to indicate the changing level of contents in a container, rather than in any details of the indicator construction shown on the drawing. In this connection, it may be added that an electrically operated indicator is shown for purposes of illustration only.

The disclosure herein made will be now rather specifically described, with the understanding at the outset however, that within the scope of the invention as claimed, numerous variations may be made.

The numeral 4 designates a wheel which is stationarily and rotatably mounted at the upper end of the container 3, with its axis disposed vertically, a bearing for said wheel being indicated by the numeral 5. The wheel 4 is driven, a small electric motor 6 being preferably provided for this purpose, and while any desired connections could be provided between the motor and the wheel, the latter is preferably in the form of a beveled

gear meshing with a beveled pinion 7 on the motor shaft.

Passing slidably through the center of the wheel 4 and having any desired driving connection with said wheel, is a shaft 8 which 60 may well be of tubular form, so that it may surround a stationary vertical guide member 9, such as a rod or tightly drawn cable, said guide member being secured in any desired manner.

Fixedly secured to the lower portion of the shaft 8 to be driven by the latter, is a level-seeking device, shown in the form of a propeller 10 which may have any desired number of blades 11, said blades being so pitched 70 as to cause ascent of the propeller through the contents of the container 3, as said propeller is driven by the shaft 8. Thus, regardless of the quantity of matter in the container 3, the propeller will always find 75 its way to the upper surface, and by moving upwardly in this manner, it also raises the shaft 8, so that the latter may be utilized to operate indicating means. As the upper level of the container contents lowers, the propeller and shaft follow by gravity.

As hereinbefore stated, the indicating means may be of any desired nature. For illustrative purposes, said means have been shown as embodying a plurality of signal 85 lights 12 whose circuits may be completed by a traveling contact 13 and individual, stationary contacts 14. For operating the traveling contact, a screw 15 has been shown, said screw being connected by appropriate 90 gearing 16 with a shaft 17, said shaft having a pulley or sprocket 18, the shaft being mounted in any desired manner. Trained over this pulley or sprocket, is a chain or other flexible element 19, one end of which 95 has a swiveled connection 20 with the upper end of the shaft 8, while the other end of said flexible element is provided with a weight 21, so as to counter-balance the weight of the shaft 8 and propeller 10, to 100 some extent.

As the propeller 10 and shaft 8 move upwardly or downwardly, according to the level of the contents within the container 3, the flexible element 19 is caused to effect rotation of the shaft 17, thus driving the screw 15 and moving the traveling contact 13 in one direction or the other, so as to effect illumination of the electric lights 12, and the operator will know that when any of 110

these lights is illuminated, the contents within the container 3, are at the level represented by said light.

It will be seen from the foregoing that simple, yet efficient means have been provided for producing the desired results, and as excellent results may be obtained from the general construction shown, it may well be followed. However, as above stated, numerous variations may be made. That is, the general construction shown may be varied and also the invention may be embodied in forms other than that herein disclosed. For instance, while the level-seeking device is shown in the form of a propeller, it might well have some other adequate form to produce the desired result.

I claim:

In an indicator for the contents of a container, a rotatably mounted wheel with its

axis disposed vertically, means for rotating said wheel, an upright tubular shaft slideable through the center of said wheel and having a driving connection therewith, a guide member passing through said shaft and serving to guide the vertical movements of the shaft, a level-seeking device carried by said shaft within the container and comprising blades pitched to cause ascent through the container contents as the shaft is rotated, said device and shaft adapted to move downwardly by gravity, the pitch of said blades causing it and the shaft to move upwardly when the shaft is rotated, indicating means, and a connection between said shaft and means whereby the vertical movement of the shaft will operate the indicator.

In testimony whereof I have hereunto affixed my signature.

GEORGE M. BECHTEL.
